(57) **CLAIM**

The ornamental design for a wearable ornament, as shown and described.

DESCRIPTION

FIG. 1 is a top plan view of a wearable ornament showing my new design;

FIG. 2 is a bottom plan view thereof;

FIG. 3 is a front side view thereof;

FIG. 4 is a rear side view thereof;

FIG. 5 is a bottom side view thereof;

FIG. 6 is a top side view thereof; and,

FIG. 7 is a perspective view thereof.

The broken lines in the drawings represent portions of the wearable ornament and form no part of the claimed design.
